Filed Feb. 17, 1964, Ser. No. 78,645

Term of patent 14 years

(Cl. D31—4)

FIG. 1 is an inverted side elevational view of a fishing rod shank showing my new design;

FIG. 2 is a top plan view of the shank;

FIG. 3 is a fragmentary bottom perspective view of the shank;

FIG. 4 is a top perspective view of the shank;

FIG. 5 is a cross-sectional view taken along the lines 5-5 of FIG. 2;

FIG. 6 is a cross-sectional view taken along the lines 6-6 of FIG. 2; and

FIG. 7 is a cross-sectional view taken along the lines 7-7 of FIG. 2.

The fragmentary broken line showings in FIGS. 1, 2 and 4 are for illustrative purposes only.

I claim:

The ornamental design for a fishing rod shank, substantially as shown and described.
